PIN FILE-FASTENER

Samuel Segal, New York, N. Y., assignor to Wilson-Jones Company, Chicago, Ill., a corporation of Massachusetts

Original application September 18, 1944, Serial No. 554,568, now Patent No. 2,498,901, dated February 28, 1950. Divided and this application February 11, 1949, Serial No. 75,790

1 Claim. (Cl. 24—153)

This invention relates to a fastener of the type ordinarily used to secure a plurality of sheets of paper or similar material together temporarily, and this application is a division of my prior application Serial No. 554,568, filed September 18, 1944, which issued as Patent No. 2,498,901 on February 28, 1950.

It is an object of this invention to provide improved means for facilitating the securing of a compressor plate to the prongs of a base member. It is a further object of this invention to provide a compressor plate with means for speeding up filing operations by decreasing the time required for manipulating the fastener. Other objects of this invention will become apparent upon reading the following description, taken in conjunction with the accompanying drawing, in which:

Figure 1 is a perspective view of one embodiment of my improved fastener secured to a stack of sheets;

Figure 2 is a cross sectional view, taken along the line II—II of Figure 1; and

Figure 3 is a detail perspective view of another embodiment of my compressor plate.

In the drawing, the reference numeral 2 indicates a base member having a pair of sheet retaining prongs 3 extending from opposite ends. The prongs may be integral with the base member, or they may be secured to the base member in any suitable fashion. A plurality of sheets 4 of paper or similar material, provided with a pair of apertures 5, is impaled on the prongs 3. A compressor plate 6, adapted to engage the prongs 3, is positioned on top of the sheets 4 between the prongs 3.

The compressor plate 6 comprises a channel member 7 having upstanding walls 8 and 9 and longitudinally extending flanges 10 and 11. The channel member 7 rests on the stack of sheets 4 and the flanges 10 and 11 are spaced from the surface of the sheets a distance sufficient to permit free sliding movement of a pair of keepers 12. The flanges 10 and 11 are upset adjacent the outer ends of the compressor plate, as indicated at 13 and 14, to restrict the sliding movement of the keepers 12. The flange 10 is provided with extensions 15 projecting beyond the ends of channel member 7. The extensions 15 facilitate assembly of the compressor plate with the sheet retaining prongs by horizontally aligning the compressor plate with the prongs. When the prongs 3 are standing upright it is necessary only to push the compressor plate transversely of the prongs until the extensions 15 engage the edges of the prongs. The prongs are then bent down-

wardly into the channel member 7 and the sliding keepers 12 are moved over them to securely retain the papers in the stack 4 in bound relationship.

5 In the embodiment of the invention illustrated in Figure 3, the compressor plate 16 comprises a channel member 17 having upstanding side walls 18 and 19, and longitudinally extending flanges 20 and 21. A pair of sliding keepers 22 and 23 is mounted on the flanges 20 and 21. Flange 21 has lips 24 and 25 turned up at its opposite ends to limit the sliding movement of the keepers.

The ends of keepers 22 and 23 sliding on flanges 20 and 21 are provided with extensions 26 and 27 which project beyond the opposite ends of the compressor plate 16 when they are in their outermost position. When the compressor plate 16 is to be assembled with a base member whose prongs 3 extend through a stack of sheets 4, extensions 26 and 27 are held in their outermost position and the compressor plate is moved between the prongs 3 in a plane parallel to the uppermost sheet 4. Movement in this direction causes extensions 25 and 26 to engage the edges of prongs 3 and thereby align the channel member 17 with the prongs so that they will be positioned in the channel when they are bent downwardly toward each other.

As each prong 3 is bent downwardly into channel 30 the keeper 22 or 23, adjacent that prong, is slid out of the way and then is slid over the prong after it has been bent, to hold the prong against accidental displacement from the channel. When sheets are to be removed from the stack, keepers 22 and 23 are each moved inwardly separately to clear the adjacent prong and the prong is then bent upwardly so that the sheets can be removed in conventional manner.

From the foregoing description it will be apparent that I have devised a compressor plate that may be brought into accurate alignment with a base member in minimum time and that the necessity of impaling apertured ends of a compressor plate on the prongs of a base member has been eliminated for both the assembly and disassembly of the fastener unit.

Although I have described two preferred embodiments of my invention in detail, it will be understood that the description thereof is illustrative, rather than restrictive, as many details may be modified or changed without departing from the spirit or scope of my invention. Accordingly, I do not desire to be restricted to the exact details of construction described, except as limited by the appended claim.

I claim:

In a fastener, a base member having a pair of sheet retaining prongs projecting therefrom, a compressor plate comprising a channel member having longitudinally extending flanges along each side of said channel member, one of said flanges being of less length than the length of said base member between said prongs to permit insertion of said compressor plate between said prongs by lateral movement, projections laterally aligned with said other flange and extending outwardly to engage said prongs when said compressor plate is moved laterally against said prongs.

SAMUEL SEGAL.

Inventor, and of the United States of America, by his attorney, filed this application for a patent on January 15, 1952.
